UNITED STATES PATENT OFFICE.

EDWARD E. REDFIELD, OF GLENDALE, OREGON.

FIREARM.

1,031,374.

Specification of Letters Patent.

Patented July 2, 1912.

Application filed August 1, 1911. Serial No. 641,817.

To all whom it may concern:

Be it known that I, EDWARD E. REDFIELD, a citizen of the United States, residing in Glendale, in the State of Oregon, have invented certain new and useful Improvements in Firearms, of which the following is a specification, reference being had to the accompanying drawings, forming a part hereof.

This invention relates mainly to magazine firearms of the general type of that shown in a pending application of the same inventor for Letters Patent of the United States, Serial No. 598,781, filed December 22, 1910, in which the several operations of extracting the empty shell, cocking the gun and placing a fresh cartridge in the chamber of the barrel, are effected by the longitudinal movements of a grip-piece which is mounted to slide on the magazine tube parallel with the barrel. The improvements covered by said former application, Serial No. 598,781, are shown and described therein as applied to a high-power rifle.

One of the general objects of the present invention is to adapt the desirable features of the high-power rifle described in said application to magazine shot guns of the same general type.

Another general object is to improve some of the features of construction of firearms of the type shown in said application, whether the same are applied to a rifle or to a shot gun.

One of the specific objects of the present invention is to improve the construction and arrangement of the take-down devices, making the construction stronger, easier to manipulate and such that the breech pressure shall be exerted against a shoulder of the receiver forward of the take-down joint and shall put no strain on the take-down devices.

A further specific object is to improve the slide locking devices, an independent slide latch being provided and acted upon directly by the finger within the trigger guard.

The invention is also concerned with the construction and arrangement of the inertia block and its coöperation with the slide.

The safety devices are of an ordinary type, but are arranged to be thrown to center or safety position by the rearward or opening movement of the breech-block. The trigger mechanism is substantially as shown in said former application, comprising a trigger lever interposed between the trigger and the sear which is mounted on the breech-block,

and coöperating with the breech-block and sear as described therein. In the present invention the cartridge lifter is modified and improved as to its construction, arrangement and operation, as will be more fully explained hereinafter.

Although the present improvements are shown and described herein as embodied in a shot gun rather than a rifle, it will be understood that they are capable of application to firearms of different types as well as that they are severally capable of use independently of each other.

The invention will be more fully explained hereinafter with reference to the accompanying drawings in which it is illustrated and in which—

Figure 1 is a view in side elevation of a shot gun in which the several features of improvements herein sought to be covered are embodied. Fig. 2 is a detail view, on a larger scale, partly in elevation and partly in longitudinal section through the receiver, frame and stock, showing the parts in the positions which they occupy when the gun is closed and ready for firing, but with the trigger locked by the safety. Fig. 3 is a view generally similar to that shown in Fig. 2, but with the safety off and the parts in the positions which they occupy immediately after firing with the trigger released. Fig. 4 is also a view generally similar to Fig. 2, but showing the breech-block in its rearward position after having restored the inertia block to its cocked position and the safety device to safety position. Fig. 5 is a view generally similar to Fig. 4 but showing the parts in the positions which they assume after the breech-block has commenced its forward movement, the lifter being shown in its elevated position. Fig. 6 is a detail view in elevation illustrating particularly the relation of the receiver and barrel to the frame and stock in the operation of taking down. Fig. 7 is a detail view in section on the plane indicated by broken line 7—7 of Fig. 5 illustrating particularly the take-down locking devices. Figs. 8 and 9 are top and under side views of the take-down locking lever. Fig. 10 is a detail view, partly in side elevation and partly broken out, showing the breech-block and some of the parts carried thereby. Fig. 11 is a view of the breech-block in end elevation as seen from the right-hand in Fig. 10. Fig. 12 is a perspective view of the trigger.

lever. Fig. 13 is a perspective view of the sear. Fig. 14 is a perspective view of the double lever which co-acts with the lifter. Fig. 15 is a top view of the lifter. Fig. 16 5 is a top view of the inertia block.

The barrel *a* chambered as usual to receive the cartridge, the magazine *b* in which the cartridges are placed and are pressed to the rear by a spring follower, not shown, the 10 receiver *c* (except as hereinafter indicated), the frame *d* (also except as hereinafter indicated), and the stock *d'*, are constructed substantially as usual in repeating shot guns. The receiver has, forward of its rear end, 15 and forward of the take-down joint, a shoulder *c'* against which the breech-block abuts in the firing position, so that the breech pressure is taken by the receiver and puts no strain upon the take-down devices. In the 20 opening of the gun the breech-block passes rearwardly below the abutment *c'* into the chamber in the frame. Forward of the front edge *d''* of the frame *d*, at the bottom thereof, is a solid extension *d''* which supports, one at each side, semi-circular lugs 25 *d''* each of which is adapted to engage a corresponding, semi-circular recess *c''*, in the receiver *c*, a hinge-knuckle thus being formed between the frame and the receiver, 30 upon which the frame and barrel hinge in the taking down of the gun. The extension *d''* and the lugs *d''* form also a vertical support and a forward longitudinal abutment to hold the receiver and the frame securely 35 together when they are locked at the top, as will now be described. In rear of the abutment *c'* the receiver *c* has an extension *c''* which is extended rearwardly and downwardly beyond the rear face or edge of the 40 receiver so as to enter the frame below the top thereof. On its upper face the extension *c''* is grooved to form a cam-lug *c''* which is adapted to be engaged by an eccentric cam-lug *d''* on the under side of a cam head 45 *d''* which is pivoted in the frame and has an operating lever *d''* which projects through the top of the frame in convenient position for operation. A spring plunger *d''*, mounted in the top of the frame, acts upon the lug 50 *d''* of the locking lever to press it normally into locking position and to hold it in locking position so that accidental disengagement of the parts is prevented. These take-down devices are most clearly shown in 55 Figs. 5-9.

The breech-block *e* is constructed, arranged and operated substantially as shown in said former application 598,781, having 60 pivoted thereon the supporting and starting lever *f*, which has a lug *f'* to co-operate with a horizontal and a vertical shoulder on the left-hand side of the receiver, not shown, to drop the rear end of the breech-block below the abutment *c'* of the receiver and to start 65 the breech-block rearwardly, being operated

for this purpose through its engagement at the lower end with the slide bar. The cocking lever *g* is pivoted upon the starting lever *f* and has a lug extended through a slot in the left hand wall of the breech-block 70 to co-operate with a shoulder *h'* of the hammer *h* which is longitudinally movable in the breech-block. The hammer is thrown forward by a coiled hammer spring, not shown, and is held in cocked position by a sear *i*, 75 also pivoted on the breech-block and adapted to be engaged by a trigger lever *r* which is actuated by the trigger *o*, all as described in said former application. The breech-block, sear and trigger lever are shown in 80 detail in Figs. 10-13.

The grip-piece *k* is mounted upon the magazine tube *b* as usual and has extended rearwardly therefrom a slide bar *k'* which has at its extremity a lug *k''* to engage the supporting and starting lever *f*. In the present construction, the lower end of the starting lever is not slotted but is formed with a hole *f''* for engagement with the slide bar *k'*, the entire rearward and forward 90 movement of the breech-block being effected through such engagement of the slide bar with the starting lever *f*. Otherwise the operation of the slide bar, starting lever, breech-block, cocking lever, hammer, sear, 95 trigger and trigger lever are substantially as described in said former application and, as they form no part of the present invention, except as they co-operate with other devices to be described, need not be further explained herein.

In the gun described in said former application, the rearward movement of the slide bar *k'* was prevented, except at the proper time, by a locking lever which stood, 105 until released, behind the starting lever and was actuated by a finger lever which projected within the trigger guard. In the present case the slide locking lever *m*, pivoted in the frame at *m'*, has at its forward 110 end a locking lug *m''* which projects upwardly within the receiver into the path of the starting lever *f* and at its rear end a button *m''* which projects downwardly within the trigger guard in position to be 115 pressed by the finger so that the lug *m''* shall be thrown down out of the path of the starting lever *f* and thereby permit the rearward movement of the slide bar. The locking lever *m* is held normally in locking position by a spring, (see Fig. 2) and the lug *m''* is so shaped that the lower end of the starting lever slips over it when the starting lever is returned to the closed position.

The inertia block *n* shown in Figs. 2, 3 125 and 4, and, in detail, in Fig. 16, is preferably in the form of a rod mounted in a sleeve *n'* which is seated in a recess in the stock *d'*. The sleeve *n'* is held in place by a tang screw *d''* which passes through the sleeve and 130

also through a longitudinal slot n^2 in the inertia block n , thereby limiting the movement of the latter. A spring n^3 mounted in a slot n^4 of the inertia block on a pin n^5 , 5 is drawn within the end of the sleeve n^1 , as shown in Fig. 2, when the inertia block is cocked, but flies out across the end of the sleeve when the inertia block moves forward, as shown in Fig. 3, thereby acting to prevent 10 the rebound of the inertia block. Furthermore, when the block is moving forward the spring acts against the end of the sleeve to throw the block forward with a snap. At its forward end the inertia block has an 15 extension n^6 which is provided with an inclined or cam end n^7 which co-operates with a cam end m^4 of a rearward extension m^5 from the slide latch or lever m so that as the inertia block moves forward (relatively) 20 the slide locking lever or latch m has its rear end thrown upward and its locking lug m^2 thrown downward to permit the slide bar to be moved rearwardly. The forward extension n^6 of the inertia block may also have 25 a cam shoulder n^8 to engage a corresponding cam shoulder m^6 of the slide locking lever or latch m , for the purpose of preventing rebound of the inertia block. The extension n^6 is also provided with a shoulder n^9 which, 30 as shown in Fig. 4, is engaged by the breech-block e in the last of its rearward movement, so that the inertia block is cocked by the rearward movement of the breech-block itself. 35 The trigger o , pivoted at o^1 in the frame, has a heel o^2 in the rear of pivot o^1 for co-operation with the toe p^1 of the safety slide p . The latter is mounted in the usual manner in the frame and has a button p^2 above 40 the upper tang for convenient operation. It is preferably arranged to have three positions. In the middle or safety position, shown in Fig. 2, the toe p^1 stands in the path of movement of the heel o^2 of the trigger so as to prevent effective movement of the trigger, but if the button p^2 is pushed over to the front or the rear of its middle position the toe p^1 stands out of the path of the heel o^2 so as to permit effective movement of the trigger. As the safety is usually pushed off by moving the button p^2 forward, its shank p^3 is so formed that in the last of the rearward movement of the breech-block, as shown in Fig. 4, it will push the safety 45 back from its forward position to its middle or safety position, so that the gun cannot be fired after reloading, until the safety is thrown off. 50 The lifter l is shown in detail in Fig. 15 and in its relation with other parts in Figs. 2 to 6, being shown in its elevated position in Fig. 5 only. It is slotted at the rear, as at l^1 , to straddle the trigger o and is pivoted upon the same pin o^1 therewith. At its forward end it is concave, as indicated at l^2 , to 55 furnish thereby a better seat for the cartridge and reduce the liability of the rolling of the cartridge out of the receiver if the gun should be held tilted toward the right. The lifter is itself lifted, as the breech-block begins its forward movement, through the intervention of a lifter lever t which is pivoted at m^1 in the frame. This lever is shown in detail in Fig. 14 and in relation with other parts in Figs. 2-5. It comprises two 60 parts or wings t^2 and t^3 . The wing t^2 stands in the same vertical plane with the cartridge stop s which is carried by the breech-block, and has a shoulder t^5 adapted to be engaged by a shoulder s^1 of the cartridge stop as the breech-block begins its forward movement from the extreme rearward position shown in Fig. 4. The cartridge stop s is pivoted in the breech-block and therefore moves freely over the wings t^2 in the rearward movement 65 of the breech-block and also yields to the action of the cam surface t^6 in rear of the shoulder t^5 as the breech-block moves forward, to permit the disengagement of the lifter lever from the cartridge stop after a 70 short forward movement of the breech-block. The wing t^3 of the lifter lever has a cam edge t^7 which, as the lifter lever is rocked on its axis by the forward movement of the breech-block, acts against the under-side of the lifter, forward of its pivot o^1 , to raise the lifter from the position shown in Fig. 4 to the position shown in Fig. 5, thereby 75 raising the cartridge which meanwhile has passed from the magazine on to the lifter 80 into line with the chamber of the barrel and in front of the breech-block, so that the cartridge shall be pushed into the chamber of the barrel by the continued forward movement of the breech-block. The lifter is not 85 sustained in its suspended position by the lever t but it has on its left-hand side a lug l^3 , which as the breech-block moves forward and while the lifter is still supported by the lever t , is engaged by an inwardly 90 projecting shoulder e^1 of the breech-block 95 which supports the lifter in its elevated position until the nose of the cartridge has been inserted far enough into the chamber of the barrel, after which the shoulder e^1 passes 100 beyond the lug l^3 and permits the lifter to 105 drop to its lowest position, as shown in Figs. 2, 3 and 6, the lifter being impelled downward by the action of the spring l^4 shown 110 in part in Figs. 2 to 4. 115 It will be obvious that the details of construction and arrangement shown will be varied more or less according to the character of the firearm to which the improvements are applied as well as that the several 120 features of improvement herein shown and described are not of necessity employed together in one and the same firearm. The invention therefore, is not limited to the precise construction shown and described 125 130

herein nor to the joint use of all of the features of improvement in one structure.

I claim as my invention:—

1. In a take-down firearm, the combination of a frame having at its lower side a forward extension with a rounded lug, a receiver having a rounded recess to engage said lug, said lug and recess forming a hinge joint between the frame and the receiver at the lower side thereof and locking devices to secure the receiver to the frame at the top thereof. 70
2. In a take-down firearm, the combination of a receiver having a rearward extension with a cam lug thereon, a frame, and a locking lever pivoted on the frame and having a cam lug to engage the cam lug of the receiver. 75
3. In a take-down firearm, the combination of a receiver having at its top a rearward extension with a cam lug, a frame, and a locking lever pivoted on the frame and extended through the same and having a cam lug to engage the cam lug of the receiver. 80
4. In a take-down firearm, the combination of a receiver having in its underside a semi-circular recess and having at its top a rearward extension adapted to enter the frame and having a cam lug, a frame having a forward extension with a semi-circular lug to engage the recess of the receiver, and a locking lever pivoted on the frame at the top and extended through the same and having a cam lug to engage the cam lug of the receiver. 85
5. In a take-down fire arm, the combination of a receiver having in its top and forward of its rear end an internal shoulder and having also a rearward extension to enter the frame with a cam lug thereon, and having also a semi-circular recess in its bottom, a breech-block movable longitudinally in the receiver, a frame having at its bottom a forward extension with a semi-circular lug to engage the recess of the receiver, and a locking lever pivoted at the top of the frame and extended through the same and having a cam lug to engage the cam lug on the receiver. 90
6. In a repeating fire arm, the combination of a frame, a receiver, a longitudinally movable breech-block, a slide bar with a connection to the breech-block, a slide latch pivoted in the frame and adapted to prevent or permit rearward movement of the slide bar and having a rearward extension with a cam end and a shoulder, and a longitudinally movable inertia block in rear of the slide latch and having a forward extension with a cam end to coöperate with the cam end of the slide latch, and having a shoulder to coöperate with the shoulder of the slide latch to prevent the rebound of the inertia block. 95
7. In a repeating fire arm, the combination of the frame and stock having a longitudinal recess, a rod-like inertia block mounted for longitudinal movement in said recess and a slide latch adapted to be actuated by the inertia block. 100
8. In a repeating fire arm, the combination of a frame, a sleeve mounted longitudinally therein, an inertia block, a spring carried by the inertia block and adapted to be drawn within said sleeve and also adapted to coöperate with the forward end of said sleeve to throw the inertia block sharply forward and to prevent rebound of the inertia block, and a slide latch arranged to be actuated by the inertia block. 105
9. In a repeating fire arm, the combination of a frame having a longitudinal recess therein, a tang screw to secure the frame and stock together and an inertia block mounted for longitudinal movement in the stock, and having an elongated slot through which the tang screw passes. 110
10. In a repeating firearm, the combination of a frame and stock having a longitudinal recess, a sleeve mounted in said stock, an inertia block within the sleeve and having an elongated slot and a tang screw to secure the stock and frame together and passed through the sleeve and elongated slot of the inertia block. 115
11. In a repeating firearm, the combination of a frame, a receiver, a breech-block having longitudinal movement in the frame and receiver, a trigger and a safety slide arranged to coöperate with the trigger to prevent effective movement thereof, said safety slide also standing in the path of the breech-block and arranged to be moved thereby from its forward-position rearward to its safety position. 120
12. In a repeating firearm, the combination of a barrel, a magazine tube, a receiver, a breech-block movable longitudinally in the receiver, a pivoted cartridge lifter, and means actuated by the movement of the breech-block forwardly from its rearward position to raise the lifter, the lifter and the breech-block having inter-engaging parts other than the lifter raising means, whereby the lifter is held in its raised position during further forward movement of the breech-block, said parts being disengaged during the final forward movement of the breech-block to permit the lifter to descend. 125
13. In a repeating firearm, the combination of a barrel, a magazine tube, a receiver, a breech-block movable longitudinally in the receiver and having a cartridge stop formed with a shoulder, a pivoted lifter and a pivoted lifter lever adapted to be engaged by the shoulder of the cartridge stop in the first of the forward movement of the breech-block and to coöperate with the lifter to raise the same. 130

14. In a repeating firearm, the combination of a barrel, a magazine tube, a receiver, a breech-block movable longitudinally in the receiver, a pivoted cartridge lifter, and
5 a pivoted lifter lever adapted to be engaged by the breech-block in the first of its forward movement and to coöperate with the lifter to raise the same, the breech-block and the lifter having inter-engaging parts
10 other than the lifter raising means, to maintain the lifter in its raised position during

further forward movement of the breech-block, said parts being disengaged during the final forward movement of the breech-block to permit the lifter to descend.

15

This specification signed and witnessed this 24th day of July, A. D., 1911.
